LOUIS THEODORE VERNEY, OF PARIS, FRANCE.

Letters Patent No. 68,471, dated September 3, 1867.

IMPROVEMENT IN PRINTING-PRESSES.

The Schedule referred to in these Letters Patent and making part of the same.

TO ALL WHOM IT MAY CONCERN:

Be it known that I, LOUIS THEODORE VERNEY, of Paris, France, have invented certain Improvements in Printing-Presses; and I do hereby declare the following to be a full, clear, and exact description of the same.

My invention consists in certain improvements, fully described hereafter, in that class of printing-presses in which the design is transferred from an engraved or etched roller to the paper.

In order to enable others skilled in the art to make and use my invention, I will now proceed to describe its construction and operation, reference being had to the accompanying drawing, which forms a part of this specification, and in which—

Figure 1 (Drawing No. 1) is a sectional elevation of my improved printing-press.

Figure 2 a plan view,

Figure 3 a section on the line 1-2, fig. 2,

Figure 4 (Drawing No. 2) an end elevation, and

Figure 5 a modification of part of the machine.

A A¹ are the side frames of the machine, which are bolted to a bed-plate, B, and are connected together by cross-bars $a a^1 a^2$. To the projecting end of a shaft, C, which turns in the side frames, is secured a cog-wheel, c¹, the teeth of which are adapted to those of a pinion on a driving-shaft, D, the latter turning in bearings on the frame A and on a frame, A², bolted to the base-plate. In vertical slots in the side frames, slide boxes or bearings in which turn the journals of a shaft, E, to which is secured a roller, E¹, the latter bearing on a smaller roller, C¹, secured to the shaft C. Round the roller E¹ is wrapped a thin flexible sheet, E², of metal, on the outer surface of which is etched or engraved, in any suitable manner, the design to be printed, the ends of the metal being connected together so as to be readily detached at a point where the roller is cut away or flattened, as shown in fig. 1; and at each end of the roller, near the flattened portion of the same, is a cam or projection, b, for a purpose described hereafter. Adjacent to the ends of the roller E¹ are two segmental plates, F F¹, through which the shaft E passes, and to each of which are connected the upper ends of two parallel rods, d d, the lower ends of the latter having screw-threads on the same, passing through a block, F², and being provided with nuts for regulating their position in respect to the said block. A pin on each block F² passes through a lever, F³, hung to the adjacent side frame, the opposite end of the said lever being connected by links F⁴ F⁵ to the side pieces f of a frame, F⁶, hung to the bar a². In suitable bearings secured to the base-plate B turns a shaft, a³, to one end of which is secured a handle or lever, a⁴; a cam, a⁵, on the said shaft, bearing against the under side of a cross-piece of the frame F⁶. In radial slots in the plates F F¹ turn the journals of rollers f¹ f² f³ f⁴, and at the side of each plate F F¹ is a segmental plate, g, which may be moved vertically to a slight extent by means of cams secured to a swinging frame, G; the journals of the lowest rollers f¹ f² f³ f⁴ bearing on the upper edges of the plates g g, so that when the latter are raised the said rollers will be lifted from contact with the roller E¹. On a rod, h, which is secured at the opposite ends to the frames F F¹, traverses a slide, G, through the rear end of which passes a roller, h¹, the latter turning in bearings in the frames F F¹; and in the said roller is a spiral groove, y, of such a character that as the roller revolves a continuous reciprocating motion on the rod h will be imparted to the slide. To the rear end of the slide G is connected a cup or reservoir, H, a hooked projection, j, at the opposite side of which rests upon a rod, h², connected to the frames F F¹, and near each end of the said rod is an inclined projection, k, for a purpose described hereafter. In the reservoir H turns a roller, l, the shaft of which is geared with that of a roller, l¹, beneath the box, and which rests on the uppermost of the rollers f¹, and at the outside of the box turns a series of rollers, l² l³, which revolve in contact with each other, the lowest roller bearing against the roller l¹ and the highest against the roller l, as shown in fig. 1. Against the roller l bears an adjustable plate, m, and from the end of the projection j is suspended a vessel, m¹, at the lower end of which is a pipe having two outlets or branches and a cock. To each of the frames F F¹ is hung a lever, n, one end of which bears against the end of one of the journals of the upper roller f¹, while the other end is in such a position as to be struck by the reservoir H when it is at the limit of its movement in either direction. To a bar, I, which rests upon the roller E¹, and slides in the side frames F F¹, is secured a sponge or strip of felt, and at each end of the bar is a pin which projects into a scroll-groove in the edge of a cam-wheel, J, secured to the shaft E. In guides on the side frames A A¹ slides a plate, K,

and on arms projecting from the inner edge of the plate are lugs $p^1 p^2$, fig. 4, so arranged as to be struck by lugs p^2 on the wheels $J J$, as the latter revolve, the plate being thus carried towards the roller E^1 . To each side frame is hung a lever, L , one end of which is connected to a rod, L^1 , attached to the plate K , and the other end of which is adjacent to the outside of one of the wheels J ; and on the latter is a pin, q , which, as the wheel revolves, strikes and depresses the lever L , and thus moves outward the plate K . To the upper side of the plate K are secured two adjustable L-shaped plates, $M M$, and to each of the latter are secured two adjustable guides or gauges, $r s$. Across both gauges $s s$ extends a plate, N , which consists of two parts, one sliding in the other, so that the plate may be extended to any required length; and through a slot in each end of the plate project two pins, $t t^1$, on the gauge s , the pins t^1 having sharp points, for a purpose described hereafter. Each end of the plate N projects over a lever, O , which is hung to the face of the plate K , and the inner end of which, when the plate is at the limit of its inward motion, is in contact with the projection b on the roller E^1 . In the frames $A A^1$ turns a shaft, P , from which project arms $u u^1$, the latter being weighted at the outer ends, and to the former is secured a plate, P^1 , which bears against the under side of the plate K , and the inner edge of which is adjacent to the roller C^1 . To a shaft, Q , turning in the side frames, are secured grooved pulleys $v v$ and a roller, Q^1 , and round the latter is wrapped a cloth, X , which passes over the roller C^1 and is secured at the opposite end to the shaft a^1 , a cylindrical bar or roller X^1 , lying within the fold of the cloth and maintaining the latter taut, as shown in fig. 1. Cords w , which pass round and are secured to the pulleys v , are attached at their lower ends to levers R , which are depressed by springs z , so that when the roller Q^1 is turned in the direction of its arrow by the cloth being drawn towards the rollers C^1 , the springs z will tend to turn the roller Q^1 back to its first position. The plates $M N r s$ are so adjusted that a sheet to be printed on, when placed between the projections $t t^1$, with its front edge against the plates $r r$, will be in a proper position to be presented to the printing-roller, the pins $t^1 t^1$ passing through the paper and perforating the same, so that, should it be necessary to pass the sheet a second time through the press, it may be adjusted to precisely the same position it first occupied. The box H is filled with printing-ink and the vessel m^1 with water. The parts of the machine are brought to the position shown in fig. 1, and a rotary motion in the direction of its arrow is imparted to the driving-shaft D^1 , when the operations of the machine will be as follows:

The reservoir H will be carried back and forth, and as it approaches each side of the machine, will strike the lever n , which is thus turned so as to move the roller f^1 laterally to a slight extent. As the roller f^1 revolves the ink in the box H will be transferred to the rollers $f^2 f^1$, and from the latter to the rollers $f^1 f^1$, the lateral motion imparted to the upper roller f^1 insuring the even distribution of the ink upon the other rollers. As the reservoir approaches the limit of its motion in either direction the projection j will pass on to one of the inclined plates h , and will be elevated with the reservoir, so that the roller t^1 will not strike the end of the upper roller f^1 as the reservoir begins to pass towards the opposite side of the machine. As the vessel m^1 is carried back and forth with the reservoir H , water will be discharged on to the roller f^3 , and will be transferred from the latter to the surface of the plate E^2 , over which it will be evenly distributed by the action of the felted bar I . After the ink has been deposited upon the plate E^2 , that upon the surface of the plate will be removed by the action of the roller f^2 . As the roller E^1 revolves the projections p on the wheels $J J$ will be brought in contact with the projections p^1 on the plate K , and the latter will be carried inward until the edge of the paper is introduced between the two rollers $E^1 C^1$, the plate P^1 guiding the paper between the rollers, when the levers $O O$ (the inner ends of which are depressed by contact with the projections b) will raise the plate N and lift the paper off the pins t^1 , so that it may be carried forward between the rollers while the plate K is moved back to its first position by the action of the pins q upon the levers L . As the plate passes between the rollers it will be pressed firmly on the cloth X , and will receive the ink from the lines in the plate E^2 , the cloth passing over the roller C^1 with the paper. After the paper has been discharged, and when the projections b are brought against the roller C^1 , the roller E^1 will be slightly raised from the roller C^1 , so that the cloth may be relieved from pressure, when it will be drawn back on to the roller Q^1 , as before. Should it be necessary at any time to raise the roller E^1 , in order to extract a sheet from between the rolls, the cam a^3 is turned so as to raise the frame F^1 , and with it the lever E^3 , block F , rods $d d$, side pieces $F^1 F^1$, and their rollers.

It will be seen that by the use of an engraved, flexible sheet of metal the necessity of renewing the printing-roller every time the design is to be changed is avoided, it only being necessary to remove the sheet E^2 from the roller E^1 , and to secure another in its place.

The devices shown in fig. 5 may be substituted for those described for turning back the roller Q^1 when the cloth is to be re-wound upon the same. In this case each cord w is secured to one end of a lever, W^1 , the opposite end of which is connected by a rod, v^1 , to the end of a bell-crank lever, Y^1 . A projection, u^1 , on the shaft E , is so arranged as to strike the short arm of the lever Y^1 when the cloth has to be drawn back, the levers being thus carried to such a position as to withdraw the cord from the pulleys $v v$ and turn back the roller Q^1 in the direction of its arrow.

Without confining myself to the precise construction and arrangement of parts herein described, I claim as my invention, and desire to secure by Letters Patent—

1. The plate K , its projections p , levers L , and connecting-rods L^1 , in combination with the shaft E , cylinder E^1 , projections p^2 and q , the whole being constructed, arranged, and operating substantially as set forth.
2. The adjustable guides r , pins t and t^1 , plates N , and levers O , arranged on the plate K , and operating in connection with the cylinder E^1 , substantially as and for the purpose specified.
3. The traversing ink-reservoir H , its rollers $f^1 f^2$, in combination with the inking-rollers f^1 , substantially as described.

4. The combination of the above, the sliding-roller f^1 , and levers $n\ n$, the whole being arranged and operating substantially as specified.

5. The vibrating bar I , operating in combination with the cylinder E^1 and its plate E^2 , substantially as set forth.

6. The traversing reservoir m^1 in combination with the cylinder E^1 , its plate E^2 , and the roller f^3 .

In testimony whereof I have signed my name to this specification before two subscribing witnesses.

L. T. VERNEY.
